MATCH BOX

Andrew Pappalardo, 186 14th St., Long Island City, N.Y.

Filed Aug. 1, 1966, Ser. No. 3,298

Term of patent 3½ years

(Cl. D48—29)

FIG. 2 is a top plan view thereof,

FIG. 3 is a front elevational view thereof,

FIG. 4 is a side elevational view thereof,

FIG. 5 is a rear elevational view thereof, and

FIG. 6 is a bottom plan view of the assembled parts.

The broken line disclosure in FIG. 1 on the drawing is for illustrative purposes only.

I claim:

The ornamental design for a match box, substantially as shown and described.
